CLOTHES DRYER

William H. Snow, Manhattan Beach, Calif., assignor to Your Pleasure Corporation, El Segundo, Calif., a corporation of California

Filed Dec. 27, 1960, Ser. No. 63,361

Term of patent 14 years

(Cl. D49—1)

I claim:

The ornamental design for a clothes dryer, as shown.
